UNITED STATES PATENT OFFICE.

JOHN FLINDALL, OF CHICAGO, ILLINOIS.

FOOT AND LEG REST.

942,630.

Specification of Letters Patent.

Patented Dec. 7, 1909.

Application filed February 10, 1909. Serial No. 477,174.

To all whom it may concern:

Be it known that I, JOHN FLINDALL, a citizen of the United States, residing at Chicago, in the county of Cook and State of Illinois, have invented certain new and useful Improvements in Foot and Leg Rests; and I do hereby declare the following to be a full, clear, and exact description of the invention, such as will enable others skilled 5 in the art to which it appertains to make 10 and use the same.

This invention relates to improvements in furniture, and particularly to an improved foot and leg rest formed so as to be readily 15 accessible and when not desired can be stowed away out of sight, and has for an object the arrangement of a slide and stop whereby the foot and leg rest is supported when in an extended position and is guided 20 to its proper resting place when it is stowed away.

A further object of the invention is the construction of a foot and leg rest in combination with an article of furniture having 25 slide ways formed therein and means connecting the foot and leg rest proper with the article of furniture so that the foot and leg rest will be supported at a predetermined angle when extended and firmly held in that 30 position by supporting lugs and sliding arms engaging a stop arranged on the article of furniture, the stop and the lugs permitting a retracting of the rest whenever desired.

35 With these and other objects in view the invention comprises certain novel constructions, combinations and arrangement of parts as will be hereinafter more fully described and claimed.

40 In the accompanying drawings: Figure 1 is a longitudinal vertical section through a chair and foot and leg rest embodying the invention. Fig. 2 is a section through the chair shown in Fig. 1 but with the foot and leg rest retracted. Fig. 3 is a section 45 through Fig. 1 approximately on line 3—3, the cover to the foot and leg rest being removed for the purpose of illustration.

50 In the provision of foot and leg rests for furniture of various kinds, as for instance chairs, it is very desirable to provide a simple and yet strong construction. Also it is very desirable to arrange the foot and leg rest to be readily moved out of the way as 55 for instance beneath the chair seat when not in use.

In constructing a foot and leg rest in combination with a chair, the same is arranged with any desired kind of rest proper and a sliding support to which the same is pivotally secured. The shielding support is arranged to slide in ways secured to the chair to which the rest is to be attached in order that the foot and leg rest proper, together with its support, may be slid beneath the 60 seat of the chair and there held until further required. In order that the foot and leg rest proper that is pivotally mounted upon the sliding support will not be pivotally mounted to an undesirable angle a lug or 65 plurality of lugs as may be desired is connected therewith and arranged to engage one of the cross bars of the chair for limiting the movement of the foot rest proper and thereby holding the foot and leg rest 70 proper at a proper angle.

In order that the invention may be more clearly understood an embodiment of the same is shown in the accompanying drawings in which—

80 1 indicates a chair which may be of any desired kind to which is secured a pair of runways or supports 2 and 3. To the supports 2 and 3 are secured guides 4 and 5 for guiding the reciprocatory movement of the 85 sliding supports 6 and 7 which are designed to rest upon the slides 2 and 3 and be held from moving toward each other by the guides 4 and 5. The sliding supports 6 and 7 are pivotally mounted at 8 and 9 to a foot 90 and leg rest 10. The sliding supports 6 and 7 are also provided with lugs or projections 11 and 12 which engage slots 13 and 14 in a cross bar or stop 15 for limiting the outward movement of the supports and for consequently limiting the outward movement of 95 the foot rest proper. As will be further seen in Fig. 3 the sliding supports 6 and 7 are pivotally mounted interiorly of the framework of the foot rest proper 10 and are 100 arranged to engage guides 4 and 5 on the outer surface thereof so that as the slides move back and forth the same are held properly in position at all times, and the lugs 11 and 12 thereof will readily engage 105 the slots 13 and 14. As the foot rest proper 10 is pivotally mounted upon supports 8 and 9, means are necessary for regulating the angle at which the same is used, and in order to supply such means lugs or stops 110 16 and 17 are secured to the framework of the foot rest proper that is arranged to en-

gage one of the cross bars 18 of chair 1 and limit the upward movement of the inner end of the foot and leg rest proper. The foot rest proper is preferably pivoted nearer the inner end than the outer end in order that the same will automatically move to the position shown in Fig. 1 ready for use immediately upon the same being withdrawn from beneath the chair shown in Fig. 2.

When it is desired to place the foot rest beneath the seat 19 of chair 1 the inner end thereof is depressed and then pushed inward until it has reached the position shown in Fig. 2. The outer end of the foot and leg rest 10 is formed with an enlarged end piece 20 that may be formed of any desired material, and either covered or not as may be desired. The end piece 20 is arranged in this manner in order to form a stop for the inward movement of the foot rest proper and also to hide from view the various mechanism employed and to present a neat and pleasing appearance. When it is desired to use the foot and leg rest a reverse procedure is employed, namely, the pulling out of the foot and leg rest proper until the lugs or projections 11 and 12 pass into the slots 13 and 14 of stop 15 and then the foot and leg rest permitted to automatically move to the position shown in Fig. 1.

The foot and leg rest has been described specifically in connection with a chair, but it will be evident that the same may be applied to couches, lounges, and any other desired piece of furniture wherever a foot and leg rest is desirable.

What I claim is:

In an article of furniture, a support, a plurality of runways, a sliding support mounted on each of the runways, a rectangular stop arranged at the rear end of each of the sliding supports, a cross bar secured to each of the runways and formed with a slot for accommodating the stops, the construction of the stops causing the cross bar to be locked against lateral movement and against removal from the support, a pivotally mounted foot and leg rest connected with the outer end of the sliding support, and angular lugs rigidly secured to the inner edge of the foot rest and leg rest and arranged to engage the support, the angularity of the lugs determining the angle of the foot and leg rest when moved to supporting position.

In testimony whereof I affix my signature in the presence of two witnesses.

JOHN FLINDALL.
